UNITED STATES PATENT OFFICE.

CARL BECKMANN, OF BROOKLYN, NEW YORK.

CARTON-UPSETTING DEVICE.

1,219,427.

Specification of Letters Patent. Patented Mar. 20, 1917.

Application filed May 1, 1916. Serial No. 94,646.

To all whom it may concern:

Be it known that I, CARL BECKMANN, a citizen of the United States, and a resident of the city of New York, borough of Brooklyn, in the county of Kings and State of New York, have invented a new and Improved Carton-Upsetting Device, of which the following is a full, clear, and exact description.

10 This invention relates to a device for upsetting or opening cartons preparatory to the receiving of the contents of the carton and constituting an essential part of a cartoning machine.

15 The invention has for its general objects to provide a device of the character referred to which is reliable and efficient in use, and so designed as to operate at a comparatively high speed.

20 A more specific object of the invention is the provision of a device of simple and novel construction for the purpose of successively feeding cartons in flat form from a hopper, opening or upsetting the cartons to receive 25 its contents, and delivering the carton to a filling, closing and sealing mechanism, the opening or upsetting being accomplished by a plurality of fingers which, in closing, cause the carton to open and then close on the other 30 diagonal from that on which they are initially folded or closed, and while held closed by the fingers, the carton is taken up by coacting rolls, which apply pressure in such a manner that when the carton passes from 35 the rolls it automatically opens out into upset form, with the flaps open, so that the carton can be filled, closed and sealed by suitable mechanism.

With such objects in view, and others 40 which will appear as the description proceeds, the invention comprises various novel features of construction and arrangement of parts which will be set forth with particularity in the following description and 45 claims appended hereto.

In the accompanying drawings, which 50 illustrate one embodiment of the invention and wherein similar characters of reference indicate corresponding parts in all the views, Figure 1 is a side view of the upsetting mechanism with a portion in section;

Fig. 2 is an enlarged horizontal sectional view on the line 2—2, Fig. 3;

Figs. 3 and 4 are sectional views showing 55 respectively a carton about to be upset and in an intermediate stage of upsetting; and

Fig. 5 is a perspective view of an upset carton.

Referring to the drawing, A designates a hopper or magazine which is composed of 60 suitably arranged upright members 1 in which cartons as they are received in flat condition from the carton-making machine are placed in a pile, the cartons being arranged in a horizontal plane one on top of 65 another. The pile of cartons B is supported on a horizontal reciprocating plunger 2 which has a forward feeding portion 3 at a lower level than the pile-supporting portion 4, and between these two portions is a shoulder 5 which engages the rear edge of the 70 lowermost carton when the follower plate is fully retracted, so that this shoulder will feed the carton forwardly from under the hopper or magazine. The plunger or follower 2 is operated by any suitable means and in timed relation to the other parts of the upsetting mechanism. When a carton is fed forwardly a pair of fingers or pins 6 enter the ends of the carton, which latter 75 slightly springs open, due to the resiliency of the material. These pins move inwardly and outwardly by suitable actuating means and in proper relation to the movement of the plunger 2. Disposed forwardly of the 80 plunger 2 are sets of pairs of fingers 7 fulcrumed on a horizontal shaft 8, and these fingers swing upwardly toward each other from the open position shown in Fig. 3 to the closed position shown in Fig. 4, and 85 thereby grip the carton B and coöperate with the restraining fingers 6 to cause the carton to open from a flat horizontal position, and then close in a vertical position. This causes 90 the breaking or flexing of the carton at the 95 folds b and b', giving the said folds the same flexibility as the folds b² and b³, which are flexed or strained in the folding of the carton by the carton making machine. Just prior to the time the carton is flattened out 100 by the closing of the jaws, as in Fig. 4, the fingers 6 are withdrawn so that the carton can be fed upwardly between a pair of coacting rolls 9, between which the carton is forced during the last part of the flattening 105 out movement. After the carton passes between the rolls it automatically opens up into square or rectangular form and remains in this position, causing creases or folds b, b', b², b³ of the same tension or flexibility. 110 The fingers 7 are opened and closed by a lazy tongs arrangement 10 receiving motion from

a reciprocatory rod or bar 11 which operates in timed relation to the plunger 2 and the holding fingers 6. The cartons, after they are set up or opened, are fed progressively 5 to the right by a reciprocatory feeder in the form of a bar 12 normally disposed above the left roll 9. This bar is supported at each end by an arm 13 which is fastened to a horizontal reciprocatory link 14 actuated by an 10 oscillating lever 15. The feeder bar 12 makes a stroke exceeding the width of the upset carton, so that each time a carton is upset it is fed forwardly to make place for the next carton. In this manner the cartons are 15 successively fed to the filling, closing and sealing mechanisms of a cartoning machine.

From the foregoing description taken in connection with the accompanying drawings, the advantages of the construction and 20 method of operation will be readily understood by those skilled in the art to which the invention appertains, and while I have described the principle of operation, together with the device which I now consider to be 25 the best embodiment thereof, I desire to have it understood that the device shown is merely illustrative and that such changes may be made when desired as fall within the scope of the appended claims.

30 Having thus described my invention, I claim as new and desire to secure by Letters Patent:

1. A carton upsetting device comprising means for feeding a flat, folded carton, fingers movable into and out of the ends of the 35 folded carton, and fingers movable toward each other and arranged to engage externally the carton at its front and rear folded edges and apply pressure to open and fold 40 the carton flat on its other folds.

2. A carton upsetting device comprising means for feeding a flat, folded carton, fingers movable into and out of the ends of the folded carton, fingers movable toward each 45 other and arranged to engage externally the carton at its front and rear folded edges and apply pressure to open and fold the carton flat on its other folds and in a plane at right-angles to the plane of the initial feeding movement of the carton, and rotating rolls between which the carton passes from the last-mentioned fingers, whereby the carton will automatically open up in square or 50 rectangular form after passing through the 55 rolls.

3. A carton upsetting device comprising means for feeding a flat folded carton, means for gripping the carton and progressively opening and folding the same flat on 60 the other diagonal from that on which it is

initially folded, and rotating rolls between which the carton passes to cause all the folds to have the same tension, whereby the carton will automatically open in square or rectangular form after passing the rolls, the 65 axes of the rolls lying in a plane parallel to the plane of the initial feeding movement of the carton.

4. An upsetting device comprising means for feeding a flat folded carton in its own 70 plane, fingers movable toward each other and into the opposite ends of the carton, swinging fingers arranged to engage the edges of the flat cartons while the first-mentioned fingers are engaged therewith, whereby the carton is folded flat in a plane at 75 right-angles to its initial plane, and rolls arranged to receive the carton and convey it away from the last-mentioned fingers, the axis on which the swinging fingers swing 80 lying in a plane passing between the rolls and in which the first-mentioned fingers lie.

5. A carton upsetting device comprising sets of swinging fingers which move open and closed, means for feeding a carton to 85 the fingers when in open position and holding the cartons centrally with respect to the fingers, means for moving the fingers toward each other while engaged with the opposite folded edges of the carton to 90 progressively open and fold the carton on the other opposite folds, and rolls arranged adjacent the fingers in such position that the carton will automatically pass to the rolls as the fingers close on the carton. 95

6. The combination of a hopper for containing a pile of cartons in flat form, a reciprocatory plunger movable under the hopper for successively feeding cartons therefrom, fingers movable into the open ends of 100 the carton fed from the hopper, upsetting fingers arranged to upset the carton, means for applying pressure to and feeding the carton from the upsetting fingers after the latter have opened and the first-mentioned 105 fingers withdrawn, whereby the carton upon leaving the means automatically opens, and a feeder associated with said means for successively feeding the open cartons therefrom, said means comprising rolls between 110 which the carton feeds in a plane at right-angles to the movement of the plunger.

7. A carton upsetting device comprising a pair of hingedly connected upsetting elements, a lazy tongs means for opening and closing the fingers, and rolls disposed in cooperative relation with the fingers for feeding away the upset carton from the fingers. 115

CARL BECKMANN.
